UNITED STATES PATENT OFFICE

JOHN KRASNODMSKY, OF MILWAUKEE, WISCONSIN, ASSIGNOR OF FIFTEEN PER CENT
TO ANTON J. KOSS, OF MILWAUKEE, WISCONSIN

FUEL TANK

Application filed January 1, 1931. Serial No. 505,992.

This invention relates to improvements in fuel tanks, and more particularly to an improved type of tank adapted for use for containing combustible fuel.

One of the objects of the present invention is the provision of an improved type of fuel tank adapted for use on aeroplanes, or motor boats, and wherever fuel is to be stored or carried, which is so constructed as to relieve the body of the tank from unusual expansion of the gases arising from the fuel therein, and also to relieve the expansion due to an explosion in the tank to reduce to a minimum any bursting of the tank due to expansion of the fuel therein.

Another object of the present invention is the provision of an improved type of fuel tank wherein the tank is provided for the escape of the expanded gases within the tank, and to convey these gases off from the body of the tank to not only reduce to a minimum the chances of explosion of such gases, but to relieve expansion in the tank due to expansion of the gases therein for preventing the bursting of the tank and causing serious injury to any persons who happen in the close vicinity of the tank.

Another object of the present invention is the provision of a tank for combustible fuel having two sets of outlets controlled by spring retained valves wherein the valves controlling one of said outlets are retained in a seated position by a comparatively light weight spring for causing the expansion of some of the gases to be spent before reaching the second outlet, and the valves controlling the second outlet are normally maintained in a seated position by means of springs which are somewhat heavier than the springs controlling the first set of valves, so as to reduce to a minimum the force of the expansion.

With the above and other objects in view, the invention consists in the novel features of construction, the combination and arrangement of parts hereinafter more fully set forth, pointed out in the claims and shown in the accompanying drawings wherein:

Figure 1 is a plan view of a combustible fuel tank constructed in accordance with my

invention with parts thereof broken away and illustrated in cross section;

Figure 2 is a side elevation with parts broken away and illustrated in longitudinal section;

Figure 3 is a sectional view on the line 3—3 of Figure 2.

Referring more particularly to the drawings, 1 indicates the main body portion of the tank which is reinforced by means of the longitudinal rods 2 and the spaced vertical rods 3. This tank is especially adapted for use for containing the fuel for aeroplanes, although it can be used equally as well as a fuel supply tank for motor boats and wherever fuel is to be stored or carried.

Arranged at each end of the tank upon the interior thereof is an inset chamber or housing 4 which opens up through the top of the body 1 as shown in Figure 2, and has a removable cover 5 which normally closes the open upper portion of the housing. Leading out from one end of the housing is a conduit 6 which has a straight portion 7 passing through an aperture in the end wall of the body 1.

It will be noted that a housing or chamber 4 is provided at each end of the main fuel tank 1 and upon the outside of the end portions of the main tank are the housings 8 into which extend the straight end portions 7 of the conduit 6. These housings 8 are elongated in form and attached to the end of the tank 1 by means of a plurality of bolts 9.

The inner wall of each housing 8 is provided with spaced valve seats, with one valve seat arranged upon each side of the outer end of the conduit 6. Extending transversely of the apertures in the bottom of the housings 8 are the guide strips 10 which carry the pins 11. These pins 11 are adapted to be received in longitudinal bores 12 which extend inwardly through the valves 13 and up into the stem thereof, as shown in Figure 3. Engaging the outer end of the stem of each valve 13 is a finger 14 carried by a vertically disposed rod 15 mounted in the upper and lower side walls of each housing 8.

Attached to the upper ends of the rods 15 are the levers 16 having coil springs 17 at-

tached to the outer ends thereof. The coil springs 17 are connected in any suitable manner to the top of the tank 1, as shown at 18.

The bottoms of the housings, or chambers 4, are provided with spaced apertures having valve seats and normally seated on these valve seats are the valve members 19 normally maintained in a seated position by means of the fingers 20 attached to the rods 21 which are rotatably mounted in the side walls of the housing 4.

Attached to the outer ends of the rods 21 are the links 22 which are connected to points on the tanks 1 by means of the coil springs 23. It will be noted from the showing in Figure 1 that the rods 21 extend from opposite sides of the housing 4 and coil spring 23 attached to one of said rods is attached to the tank at a point remote from one end thereof, while the coil spring attached to the other rod 21, through the medium of link 22, is attached to the body 1 adjacent the end thereof.

The springs 23 are somewhat lighter in weight than the springs 17, so that gases escaping past valves 19 will have a great deal of their expanded force spent before reaching the valves 13.

Extending outwardly from the opening side of each housing 8 are the conduits 24 which carry off the expanded or exploded gases.

Leading in through the top 5 of each housing 4, is an air vent pipe 25 and this vent pipe extends down through the conduit 6 and past the end of the straight portion 7 where it projects into and beyond the housing 8. The conduit 24 is attached at its inner end to the reduced end portion 26 of housing 8 and leading in through the top wall of housing 8 is an air vent pipe 27 which passes into the conduit 24, as shown in Figure 2.

It will be apparent from the foregoing that any expansion of an accumulation of gases within the tank 1 will have a tendency to first open the valves 19, relieving the expanding gases from the body of the tank. At this point, a certain amount of the force of the expansion of the gases is spent through the opening of valves 19, due to the tension of the springs 23.

As the gas continues outwardly through the housing 4 into conduit 6, considerable air is mixed with these gases through the air vent pipe 25, as the force of the passage of the gases, through conduit 6 will have a tendency to draw fresh air down through the air vent pipe 25. When the expanded gases reach the valves 13, these valves can be readily forced to an open position against the tension of springs 17 and the gases passing out into the conduit 24. The force of the gases passing through conduits 6 and 24 will have a tendency to draw a fresh supply of air into the conduits, through the air inlet pipes 25 and 27.

The tank is provided with the usual filling nipple 27 and engaged over the top of this nipple is the cover 28 which carries the usual indication gauge for ascertaining the amount of gases in the supply tank.

It will be apparent from the foregoing that two sets of valves are arranged to retard and spend the expansive gases issuing from the tank 1, due to the accumulation of the gas therein. An excess accumulation of gas within the tank may be passed out through the valves 19 and thence on through the valves 13. This expansion of the gaseous fuel within the tank reduces to a minimum the causes for explosion, and even though an explosion takes place within the tank, it will be noted that the tank is heavily reinforced by the rods 2 and 3, and as the escape valves are arranged in each end of the tank to provide for the escape of the gases, even in an unexpanded condition, these valves will permit the passage of the gas out through the conduits 24, and due to the fact that the springs 23 which control valves 19 are somewhat lighter in weight than the springs 17, a great deal of the expanded gases will be spent before they reach the valves 13.

However, there will be a sufficient amount of expansion to cause the valves 13 to open against the tension of the springs 17 and permit the escape of the gases.

The air inlet pipes 25 and 27 will have a tendency to supply the outlet conduit 24 with fresh air to reduce to a minimum the return of any gases to the interior of the body of the tank, as the expanded gases leaving the tank will set up a suction through these air inlet pipes 25 and 27 and create a circulation of fresh air to be mixed with the gas.

It will be noted from the foregoing description taken in connection with the accompanying drawings, that this type of tank can be constructed at a comparatively low cost. Where a tank is designed for containing approximately 65 gallons of fluid, a 14-gauge plate would be sufficiently heavy for the construction of the tank and the thickness of the plate will increase one gauge for every tank built for each additional 20 gallons. It will also be noted that the device in its construction can be either wound or riveted and can be made to carry or store fuel as the case may require.

While I have shown and described the preferred embodiment of my invention, it will be apparent from the foregoing that slight changes may be made in the construction when putting the invention into practice without departing from the spirit of the same or the scope of the appended claims.

I claim:

1. A fuel tank having spaced outlets at the ends thereof, a housing in the body of the tank adjacent each end having spaced openings communicating with the interior of the

5 tank, an outlet conduit for each housing extending through the end walls of the tank, spring controlled valves for both sets of outlets in each end of the tank, and the springs for controlling the valves of one set of outlets being of greater tension than the springs for controlling the valves of the second set of outlets.

2. In a fuel tank having two sets of outlets
10 at each end thereof, spring controlled valves covering the passage of fluid through said outlets, whereby to cause some of the force of the expansion of gases in the tank to be spent while passing through the first set of outlets
15 to engage the valves at the second set of outlets, and means for introducing a draft of fresh air into the gaseous fluid as it leaves the tank.

20 3. A fuel tank having spaced valve controlled outlets at each end thereof, means controlling the movement of the valves in said outlet for retarding the expansion of the fluid as it passes through said outlets, and means for introducing a supply of fresh air into the
25 gases after passing through both sets of outlets to reduce to a minimum the return of any of the gases in the tank.

4. A fuel tank including a substantially rectangular body, brace rods extending longitudinally and vertically of the tank for reinforcing the same, valve controlled spaced outlets at each end of the tank, means for applying a yieldable tension to the valves for retarding the movement of the expanded
35 gases upon passing through the outlets, and means for introducing air into the gases as it leaves both sets of outlets.

50 In testimony that I claim the foregoing I have hereunto set my hand at Milwaukee, in
40 the county of Milwaukee and State of Wisconsin.

JOHN KRASNODMSKY.
